UNITED STATES PATENT OFFICE

2,202,767

PLANER

Alfred Trosch, Rochester, N. Y., assignor to Consolidated Machine Tool Corporation, Rochester, N. Y., a corporation of New York

Application August 3, 1939, Serial No. 288,238

12 Claims. (Cl. 90—27)

This invention relates to planers and more particularly to machines adapted to plane and finish very large pieces of flat work such as ship plate, such work pieces ranging to a dimension of fifteen feet in width and forty feet in length. For the planing and finishing of such work pieces it is very desirable, and of great advantage, that the work piece may be planed and finished at one setting thereof, both as to its surface, its sides,— and also as to its ends,—which ends are often not at right angles to the sides of the piece. A principal object of the invention is to provide means whereby in a single structure, and with a single setting of the work piece, not only the sides and surface of the same may be planed and finished, but also the ends, which may be at more or less an angle other than a right angle to the longitudinal axis of the work piece.

To these ends the invention as herein shown is embodied in a machine of double run-way, traveling cross-rail type, the work to be planed being mounted on a suitable work holding device between the run-ways. The invention comprises mechanism for planing not only the surface and sides of the work piece, but also the ends thereof, and still further, provision for planing the more or less oblique ends of the work piece and for planing scarfing cuts therein. It is desired at this point to emphasize the advantage gained with the construction of the present invention of not having to move and re-set these large work pieces to completely finish the surface, sides, and also the ends thereof.

The foregoing and other objects and advantages of the invention will be better understood from the following detailed description taken in connection with the accompanying drawings, and the distinctive features of novelty will be thereafter pointed out in the appended claims.

Referring to the drawings,

Figure 1 is a side elevation with portions broken away of a planer embodying the invention;

Figure 2 is an end view thereof and transverse section on line 2—2 of Figure 1;

Figure 3 is a plan view thereof with the planer heads and mountings omitted;

Figure 4 is a lengthwise vertical section on line 4—4 of Figure 3 and showing the mounting of the work piece;

Figure 5 is an enlarged detail view partly in elevation and partly in transverse section approximately on line 5—5 of Figure 3;

Figure 6 is a detail horizontal section on line 6—6 of Figure 5;

Figure 7 is a detail view partly in elevation

and partly in transverse section approximately on line 7—7 of Figure 3;

Figure 8 is a horizontal detail section on line 8—8 of Figure 7;

Figure 9 is an end view and transverse section 5 similar to Figure 2 but showing a planer head equipped with a taper attachment for planing scarfing, or taper cuts at the sides or ends of the work; and

Figure 10 is a detail elevation looking endwise 10 of the cross rail, of the form shown in Figure 9.

10, 11 indicate the two spaced apart run-ways of the machine which is generally of the usual traveling cross-rail type. In troughs provided 15 in the upper faces of these runways screws 12, 13 are mounted, these screws being supported in the usual manner on bronze shoes spaced at intervals throughout their length, and being equipped with suitable end thrust bearings at 20 each end thereof, and with long bronze nuts borne by the saddles to engage the screws, these features being of usual construction and not herein shown. The two screws 12, 13 are driven by a reversing drive motor 14 having shaft extensions 15, 16 from its respective ends which are connected to the screws 12, 13 by suitable gearing. The motor 14 which operates the cross-rail may be controlled in the usual manner by a master switch mounted on one of the cross-rail saddles, and engaging adjustable dogs on the run-way as is usual in this general type of machine. 15, 16 denote saddles fitted to operate 25 on run-ways 10, 11 and bearing long bronze nuts engaging the screws 12, 13 in the usual manner. 30 17, 18 denote pedestals mounted on these saddles, and to which the ends of the cross-rail 19 are secured. One feature of the present invention relates to means for optionally mounting 35 and clamping this cross-rail to extend in a direction other than at right angles to the longitudinal extent of the run-ways, and for this purpose one of the pedestals on which the cross-rail is mounted, shown as the pedestal 17 is pivoted for turning movement on the saddle 15; 40 this pedestal base having for this purpose a short depending circular boss or projection 17A which fits a socket recess provided therefor in the saddle 15. This pedestal is firmly clamped to the saddle in any adjusted condition by a series of 45 50 clamp bolts 17D which are passed through arcuate slots 17B of the base flange 17C of the pedestal and screwed into holes tapped therefor in the saddle. The other pedestal 18 is permitted the requisite movement for the swing- 55

ing of the cross-rail by having bolts 20 with T-heads engaging a series of parallel undercut T-slots 20A of the saddle. These bolts extend upward through short transverse slots 20B of the flange base 18A of the pedestal 18 which is engaged by nuts threaded on said bolts. 20C indicates a means for adjusting the pedestal with respect to the saddle comprising a screw with geared connection to a wrench engageable member—it being understood that such means is merely illustrative of any suitable means for accomplishing this result. The cross-rail 19 is thus adapted to be adjustably clamped so that tool heads thereon may plane the end edge portions of work which are at other than right angles to the longitudinal extent of the work as indicated at W' on the work piece W. Such work piece W is mounted on a suitable work holder shown as comprising a series of steel beams 21 extending between the run-ways. The work is clamped to these beams by suitable straps and bolts 21A. In order to properly hold these large work pieces and still leave the side and end edges clear for the operation of the tools, it is found desirable to tap these work pieces underneath to receive the strap bolts 21A. The work piece as illustratively shown in Figure 4 is tapered longitudinally, and the straps and bolts 21A are provided with the requisite filler pieces 21B so as to block up the work piece and present its top surface in a horizontal plane. 21C, 21D denote end stops for the work piece which may be removed when cross planing the ends of the work as presently described.

As shown in Figure 2, two swiveling type planing heads 22, 23 are adjustably fitted on the cross-rail 19, the head 22 being shown as adapted for planing the top surface of the work, and the head 23 shown as having a depending extension 23', bearing a tool head 23'' adapted for planing the longitudinal side edges of the work piece. When these heads are in use the cross-rail is operated back and forth along the run-ways by the driving motor 14 as already set forth. Motors 24, 25 are provided at the ends of the cross-rail with driving screw connections 24A, 24B for horizontally moving the planing heads 22, 23 respectively along the cross-rail and motors 26, 27 borne by the respective tool heads are provided with screw connections indicated at 27A in Figure 9 for moving the tool rams vertically and angularly on their respective heads 22, 23. The operation of these several motors is in practice automatically controlled by switch mechanisms well known in the art and which it is not deemed necessary to illustrate herein.

In accordance with my invention a third planing head 28 is mounted for movement along the cross-rail 19. This planing head is equipped with a reversing drive motor 29, which through spiral gearing 30 operates a spiral gear 31, mounted on said planing head to engage a rack 32 on the cross-rail for driving said planing head along the cross-rail. It will be understood, however, that this planing head could also be screw driven in a similar manner as already described for the cross-rail drive, with a course only one screw being required—this screw being driven by a reversing planer drive motor similarly as the motor 14 for the cross-rail. In accordance with my invention the planing saddle 28, which constitutes the novel cross-planing device of my invention is equipped with an auxiliary rail support section 33 extending outward at right angles from the saddle and the cross-rail, it being noted that this

saddle 28 is mounted on one side, i. e. on the rear face of the cross-rail while the saddles bearing the tool heads 22, 23 are mounted on the other side, i. e. on the front face of the cross-rail. This rail section 33 has slidably fitted thereon for horizontal movement, a saddle 33A bearing a cross planing tool head 34, the tools 34A of which are adapted to plane, and scarf or finish the ends of the work piece W. In such operation the cross-rail 19 is held stationary and the tool head 34 is driven back and forth along said cross-rail by the drive imparted from the motor 29. The necessary small horizontal feed movement of the saddle 33A and the cross-planing tool head 34, on the auxiliary rail 33 in a direction transverse of the cross-rail, is derived from the motor 35, borne by the saddle 28 through a usual screw or like connection to the saddle 33A from said motor. The tool head 34 has mounted at the top thereof a motor 36 for imparting the necessary vertical and angular movement to the tools 34A.

By the mounting of the cross planing tool head 34 on the auxiliary rail 33 extending at right angles to the main cross-rail it is possible to feed the head 34 in this direction at the end of each cross planing stroke when planing horizontal surfaces at the ends of the work, such as scarfing cuts, and also to feed the tool in towards the work between successive planing cuts across the vertical surfaces of the ends of the work. The main cross-rail 19 is clamped to the run-ways when using the cross planing head, and this auxiliary rail 33 enables the tool head 34 to be moved or fed small amounts in a direction parallel with the longitudinal centerline of the machine, without having to move the whole cross-rail after it is positioned and clamped.

My invention also comprises improved means for producing scarfing or taper cuts along any one of the four sides of the work piece. For this purpose it is contemplated that each of the described tool heads will be arranged to receive the taper attachment to be now described, though it is herein shown as applied to only one of them. Referring to Figure 9 the tool head 22' mounted in the saddle 220 and slidable on the cross-rail 19, has feed movement imparted thereto from the motor 26' through worm gearing 26''. Brackets 37, 38 are attached to the cross-rail at a proper distance each side of the saddle 220 and have clamped thereto a taper bar 39 which extends across the face of the planing head. The taper bar 39 is clamped to brackets 37, 38 so that it extends at the precise angle of the scarf to be planed as indicated at S on the work piece W. 40 denotes a precision limit switch mounted on the face of the tool ram 22'' of the planing head 22'. This switch controls the operation of motor 26' and therefore causes the tool to be fed downwardly along with its lateral feed just enough to produce the scarfing cut S. It will be understood that a like result and employing a similar taper bar might be obtained by mechanically controlling the downward feed of the tool, instead of doing this by an electric motor. The described machine is thus adapted to finish completely with a single setting of the work piece, a flat work plate that is either rectangular or with one or both ends thereof at more or less of an oblique angle, and to finish both the top surface, the side edges, and the end edges of the piece, as well as to produce scarfing cuts along any one of these edges.

I am aware that the invention may be em- 75

bodied in other specific forms as to its several features, without departing from the spirit or essential attributes thereof, and I therefor desire the present embodiment to be considered in all respects as illustrative and not restrictive, reference being had to the appended claims rather than the foregoing description to indicate the scope of the invention.

Having now described my invention, what I claim as new and desire to secure by Letters Patent is—

1. A planer comprising a cross-rail mounted at its opposite ends on run-ways, with means for moving the same along said run-ways, adapted to have means mounted thereon for planing a work piece by such cross-rail movement, and means borne by the cross-rail mounted for movement transversely outward therefrom for planing an end of the work piece by an operative movement along the cross-rail transversely of the run-ways.

2. A planer as described in claim 1 wherein the last named means embraces a saddle fitted to slide on the cross-rail with means for moving it thereon, said saddle having a rail support extending outward therefrom with a second saddle mounted for movement on said rail support transversely with respect to the cross-rail, and a planing tool head borne by the last named saddle.

3. A planer comprising a cross-rail having its ends supported on spaced apart run-ways adapted to receive a work piece therebetween, with means for moving the cross-rail along said run-ways, a saddle mounted for movement on said cross-rail and having means for moving the same therewith, said saddle having a rail support extending outward therefrom transversely away from the cross-rail, a second saddle mounted to move on said rail support with means for moving the same thereon, and a planing tool head borne by said second saddle adapted to plane ends of a work piece by a working movement transverse of the run-ways.

4. A planer comprising spaced apart run-ways adapted to permit a work piece to be mounted therebetween, a cross-rail mounted on and movable along said run-ways, means for adjustably positioning the mountings of the cross-rail on the run-ways with respect to each other, clamp means borne by said mountings arranged to permit the cross-rail to be clamped in positions at angles other than rectangular with respect to the run-ways, and a saddle bearing a planing head mounted on said cross-rail.

5. A planer as described in claim 4 wherein saddles with pedestals resting thereon are provided on the runways as mountings for the ends of the cross-rail, with a connection constructed and arranged to permit limited swiveling of one end of the cross-rail on its saddle support, and permitting the other end of the cross-rail to be

clamped in different positions with respect to its saddle.

6. A planer comprising spaced apart run-ways adapted to receive a work piece between them, a cross-rail mounted for movement along said run-ways, such mountings at the cross-rail ends being adjustable with respect to each other and having clamp means constructed and arranged to permit the cross-rail to be held rectangular with respect to the run-ways, or at an oblique angle with respect thereto, at will, and a saddle bearing a planing head mounted for movement on said cross-rail.

7. A planer as set forth in claim 6 wherein the planing head is mounted for a two-direction movement—along the cross-rail with the saddle, and horizontally toward and away from cross-rail and saddle.

8. A planer comprising spaced apart run-ways having a cross-rail mounted for movement along said run-ways and with a capability of angular adjustment with respect to said run-ways, adapted to have planing heads mounted at one side thereof to plane the top surface and longitudinal sides of a work piece, and a planing head mounted at the other side of said cross-rail with a provision for movement along the cross-rail, and also in a horizontal direction transversely thereof, the last named tool head adapted to plane end edges of a work piece by a working movement along the cross-rail and transversely of said run-ways.

9. A planer comprising spaced apart run-ways, a horizontal cross-rail mounted for reciprocating movement therewith to effect working cuts, a saddle mounted for movement on the cross-rail, a tool head mounted for vertical movement in the saddle, means for feeding the saddle along the cross-rail, and means for at the same time feeding the tool head downward at a predetermined rate to effect a scarfing cut in the work.

10. A planer comprising spaced apart run-ways, a horizontal cross-rail mounted for reciprocating movement therewith to effect working cuts, a saddle bearing, a tool head mounted for feed movement horizontally along the cross-rail, and means for feeding said tool head downward in the saddle at a predetermined even rate as it is fed laterally, to effect a scarfing cut in the work.

11. A planer as set forth in claim 10, wherein a taper bar is adjustably fixed to the cross-rail, and has means cooperative therewith for controlling the taper feed of the tool head.

12. A planer as set forth in claim 10, wherein the tool head is equipped with an electric motor for effecting the feed movement of the tools, with a precision limit switch controlling such motor, and with a taper bar adjustably borne by the cross-rail for controlling said switch.

ALFRED TROSCH.
